Primary Examiner — Kelley Donnelly*(74) Attorney, Agent, or Firm* — Buchanan Ingersoll & Rooney PC(57) **CLAIM**

The ornamental design for storage tub, as shown and described.

DESCRIPTION

FIG. 1 is a top perspective view of our storage tub;

FIG. 2 is a front view thereof, the rear view being a mirror image thereof;

FIG. 3 is a top view thereof;

FIG. 4 is a bottom view thereof; and,

FIG. 5 is a left side view thereof, the right side being a mirror image thereof.

The broken line showing in FIGS. 2 through 5 are for the purpose of illustrating the environment of the design only and form no part of the claimed design.

1 Claim, 5 Drawing Sheets*FIG. 2*

FIG. 3

FIG. 4

FIG. 5
